CARD AND ENVELOPE FEEDING APPARATUS

Harmon P. Elliott, Watertown, Mass., assignor to The Elliott Addressing Machine Company, a corporation of Massachusetts

Application May 12, 1933, Serial No. 670,644

14 Claims. (Cl. 271—2)

This invention comprises certain improvements in the general type of apparatus shown and described in my Patent No. 1,909,910, dated May 16, 1933, for "Addressing and printing apparatus", and relates more specifically to improvements on means for feeding the cards or envelopes from the bottom of the stacks thereof placed in suitable magazines and pushing them forward through suitable guides to the printing zone. 10 Heretofore it has been customary to employ a rotary drum located beneath said magazine provided with suitable even curved surface, part of which has been roughened to produce a frictional contact with the bottom card or envelope, 15 and a set of spring plates forming a gate at the lower wall of the wall of the magazine under which the cards or envelopes have to be forced. This general arrangement has proved rather delicate of adjustment and not always satisfactory in operation. Also, the friction contact of the drum with the card or envelope sometimes does not continue through a sufficient arc of travel to insure the front end of the card or envelope being projected far enough into the 20 printing zone to make certain that it will be securely grasped by the printing mechanism.

In the present invention these difficulties have been overcome by providing the feed drum with raised portions extending part way around the 25 cylindrical surface thereof and in substantial contact with the lower edge of the gate, the cutaway sections between said raised portions being sufficient in depth to permit a card or envelope lying therein to pass under the gate, which makes it possible to use a solid plate for said gate and adjust it permanently for cards or envelopes of given 30 thicknesses.

Also, such feeding drum according to the present invention is provided with spring fingers projecting from its surface at points near the rear end of the frictional section thereof, which said fingers will flex downward while passing under the gate, or any other rigid portion of the apparatus in their line of travel, but will extend 35 away from the drum at other times in a position such that they can engage the rear end of each card or envelope and give it a supplemental push after the period of frictional contact between the card or envelope and the drum has terminated.

50 The present invention also has for its object certain other minor improvements in construction of elements cooperating for the general purposes above described, which will be hereinafter pointed out.

55 The best forms of apparatus at present known

to me embodying my invention are illustrated in the accompanying sheet of drawing, in which

Fig. 1 is a vertical section taken through one end of a postcard and envelope printing apparatus such as described in my above mentioned Patent No. 1,909,910, to which one form of my present invention has been applied. 5

Fig. 2 is a perspective view of the improved form of feed drum employed in said invention.

Fig. 3 is a detail section on an enlarged scale 10 through the said drum and adjacent end of the gate cooperating therewith.

Fig. 4 is a perspective view of one form of spring finger which may be attached to said drum, and 15

Fig. 5 is a detail side elevation of the drum with such finger mounted thereon in position for cooperating with a postcard which is being fed to the printing zone by it.

Fig. 6 is a perspective view of another form 20 of spring finger and apparatus for mounting it on the drum, and

Fig. 7 is a detail side view of a portion of the drum showing said modified form of finger mounted thereon. 25

Throughout the drawing like reference characters indicate like parts. 51 represents a portion of the main frame supported on legs, one of which is shown at 52, and having the table surface 66, which is cut away to permit a portion of the feed drum 23 to project upwardly above the plane of the table a slight distance. The drum 23 is mounted on a revoluble shaft 54 journaled in the main frame 51 and is rotated by any suitable means, not shown. 30

24 indicates generally the magazine in which is placed a stack of envelopes or postcards 21, which are to be printed, the lefthand edge of the bottom card or envelope resting on said drum 23, while the right hand or rear edge is supported in any convenient way, as by the bent wire frame 53. The front wall of the magazine 24 is shown at 122 and on the lower end thereof is mounted the gate 124, the purpose of which is to prevent more than one card or envelope at a 40 time being pulled off the bottom of the stack by the feed drum 23 and pushed forward under the pressure roller 132 into the guides 22 which lead to the printing zone. 50 represents generally a magazine for a stack of card stencils (not shown) 45 which may be simultaneously fed forward to the printing zone one by one as described in my said above mentioned patent. 50

In the particular construction here shown the cylindrical surface of the drum 23 is provided 55

with a central band 1 having a thickness such that when the gate 124 is properly adjusted only one card or envelope can pass between the two, as best shown in Fig. 3. Said drum is also provided with edge flanges 2, 2, which are of such thickness in directions radial to the drum that they are substantially in contact with the lower edge of the gate 124, if the latter is wide enough, or such that their outer surfaces will be substantially tangent to the plane of said gate edge if they are spaced apart widely enough to avoid contact with said gate. Said flanges 2, 2, are cut away along a portion of the drum surface approximately equal to the length of the postcard or envelope being fed, so that such postcard or envelope may fit in to the cutaway space 14 so formed between the raised portions of the drum surface formed by the flanges 2, 2. Consequently such postcard or envelope resting in this cutaway section may be slid under the gate 124 if the drum has sufficient frictional action on said card or envelope to pull it out from under the rest of the stack. To insure sufficient frictional action of this character tapes 35, 35, of relatively soft and elastic composition, such as rubber, are fastened to the surface of the drum 23 in the cutaway portion 14 and preferably in line with the flanges 2, 2. As shown, the edges of the drum are provided with slots 13, 13, and the tapes 35, 35, have thickened ends 12, 12, so that when the thinner portions adjacent the tape ends are stretched and slipped into the slots 13, 13, the contraction of the elastic tape will cause the thickened ends 12, 12, to become wedged in said slot and hold the tapes in the position shown, said tapes being nearly equal in length to the length of the cutaway sections 14, 14, of the side flanges 2, 2, and having to be stretched before being mounted on the drum as above described.

40 The tapes 35, 35, are preferably made of a thickness about equal to that of the central band 1 so that a card or envelope grasped by them can be pushed under the gate 124, and preferably the upper surfaces of these tapes are serrated or otherwise roughened as best shown in Fig. 2.

50 In operation of the above described apparatus, when the drum is rotated in the direction of the arrow in Fig. 1, the contact of the raised rib portions 2, 2, of the drum with the gate 124, or their elevation in case they are on either side of the gate, will hold up the stack of postcards 21 in magazine 24 in a position such that the bottom card cannot be slid under the gate until the 55 cutaway portions 14, 14, of said ribs come under the gate, whereupon the front edges of the stack of postcards will drop so that that of the bottom card will be opposite the space between the drum and the lower edge of the gate 124, and thereupon the frictional action of the tapes 35 will slide said bottom postcard under the gate, as shown in Figs. 1 and 3. After the bottom postcard has been pushed under the gate the raised portions of the ribs 2, 2, will thereafter 60 prevent other cards dropping down to positions such that they can pass under the gate, and this condition will continue until the drum has made a complete revolution and the above described operation is repeated.

65 70 To further facilitate the co-action of the drum and gate I prefer to have the axis of the drum offset slightly to the left of the plane of the gate, as shown in Fig. 1, and to have the surface of the lower end of the gate backed off slightly as shown in Fig. 3, so that it will practically lie in

a plane substantially parallel to a plane tangent to the surface of the drum at that point.

139 indicates the usual weight sliding vertically on the magazine wall 122 and provided with a spring clip 138 for holding it in elevated position. When not held in this elevated position it rests on the forward edge of the stack of postcards and serves to insure the bottom postcard being held down in contact with the rotating drum. Preferably the width of this weight in a direction 10 parallel with the axis of the drum should be considerably less than the distance between the two drum flanges or ribs 2, 2, as otherwise there would be a tendency for this weight to cause the outer side edges of the last few envelopes in the 15 stack to tilt upward so far as to prevent the bottom one from being fed under the gate.

20 In the operation, as above described, the cards or envelopes in the magazine 24 are successively pulled out of the magazine and fed forward under 25 the pressure roller 132 into the guides 22, and, so long as the card is in contact with roller 132, the frictional feeding action of the drum continues. Thereafter, however, the momentum of the card alone tends to push it forward, and as 25 this in certain cases may be insufficient to push it far enough into the printing zone, I provide the drum in the present invention with flexible wire fingers 4, 4, or pivoted fingers 7, 7, which are located near the rear ends of the friction tapes 35, 30 35, and will continue to engage the card and force it forward after it has left the roller 132, as shown in Fig. 5.

35 The wire fingers 4, 4, may be mounted on little grooved shoes 3, 3, which can be slipped under 35 the rear portions of the elastic tapes 35, 35, as shown in Figs. 2 and 5.

40 The pivoted fingers 7, 7, are mounted on a shaft 6, which is journaled in a crank member 5, which may be mounted on the drum shaft 54 40 by any convenient means such as the clamping plate 9 pivoted to member 5 at 10 and engaging the setscrew 11 at its other end. The spiral spring 8 is anchored at one end in the member 5 and at its other end in the crank 6, thus serving to yieldingly maintain the fingers 7, 7, in the 45 positions shown in Figs. 6 and 7, such that they will project away from drum 33 normally but can be bent downward when engaging the gate 124 or the table 66, or other rigid portion of the 50 main frame. When in the position shown, the fingers 7 operate in the same way as described with reference to the wire fingers 4, 4, to give the postcard or envelope the supplemental push after the frictional feeding action of the drum has 55 ceased.

60 Among the advantages of the invention may be mentioned the simplicity of the gate construction and the certainty of card or envelope feeding action by the cutaway feed drum cooperating therewith, and the supplemental feeding action of the spring fingers on the drum which insure even short cards or envelopes being pushed into the printing zone.

65 Various changes in the details of construction shown and described could be made without departing substantially from the principles of operation of my invention and the character of results obtained thereby.

70 Having described my invention, I claim:

75 1. In a printing apparatus comprising a magazine for holding a stack of envelopes, cards, or similar articles, to be printed, and a revoluble drum for feeding them one by one out of the bottom of said magazine under a gate and toward a 75

- printing zone, the combination, with such gate, of raised sections of the circumferential face of such drum movable approximately in line with the adjacent edge of such gate, but cut away 5 along an arc substantially equal in length to the length of the article being fed, and to a depth at least equal to the thickness of such article, whereby, during the portion of drum rotation in which said raised surface portions are moving 10 under such gate, no card can be fed out by it, but, when said cutaway surface portion comes under the magazine the bottom article therein may drop into said cutaway space and be shoved under such gate by further rotation of such drum.
- 15 2. A combination such as defined in claim 1 in which the axis of such drum is offset to one side of a plane in which such gate lies, and the gate comprises a solid plate having its edge adjacent the drum backed off so that the edge surface thereof shall be substantially parallel to a tangent 20 to the drum surface at that point.
- 25 3. A structure such as defined in claim 1 in which said raised drum surface portions consist of circumferentially extending side flanges thereon, combined with a circumferential band extending around such drum between said flanges and having its outer surface spaced away from such gate a distance substantially equal to the thickness of the article being fed from the magazine.
- 30 4. A structure such as defined in claim 1 in which said raised drum surface portions consist of circumferentially extending side flanges thereon, combined with a strip of yielding material extending circumferentially along nearly the entire length of said cutaway portion of such drum surface, and having a thickness less than that of 35 said side flanges.
- 40 5. A structure such as defined in claim 1 in which said raised drum surface portions consist of circumferentially extending side flanges thereon, combined with two strips of yielding material extending circumferentially along nearly the entire length of said cutaway portion of such drum surface, and each, having a thickness less than 45 that of said side flanges, one of said strips being in line with each of said side ribs.
- 45 6. A structure such as defined in claim 1 combined with a weight freely movable in vertical guides along such gate and resting on such cards or envelopes.
- 50 7. A structure such as defined in claim 1 combined with a weight freely movable in vertical guides along such gate and resting on such cards or envelopes, said weight having a width transversely of said raised sections considerably less than the distance separating the latter one from the other.
8. A revoluble drum for feeding cards or envelopes successively out of the bottom of a magazine, comprising a cylindrical surface portion having slots in its edges and a tape of relatively elastic rubber composition of a length approximately equal to but normally less than the distance between said slots, having their extreme end portions integral with the body thereof, but thicker than the width of said slots and the sections adjacent said ends being of a thickness such that 10 said sections can be slid into said slots when the body of the tape is slightly stretched; whereby, when said tape ends are confined in said slots the rest of the tape will be under tension upon the drum surface between said slots.
- 15 9. A combination, such as defined in claim 8 in which the outer one of said tape surfaces is serrated.
- 20 10. The combination with a revoluble feed drum for feeding cards or envelopes from the bottom of a stack in a magazine, of an elastic tape extending circumferentially along a portion of such drum surface and fastened thereto at its ends, and a shoe fitting under said tape and provided at one end with spring fingers, the free ends 25 of which project away from said drum surface when said shoe is in position under said tape.
- 25 11. In an apparatus for feeding a succession of cards or envelopes out of a magazine from the bottom of a stack therein, comprising a revoluble 30 drum located beneath such magazine and having a section of its surface formed to frictionally engage any card or envelope pressed down on it, together with guides for such cards after they have been pulled out of the magazine by 35 such drum, the combination, with said above described apparatus, of a plurality of spring fingers mounted on said drum adjacent the rear end of said friction section of its surface and projecting outwardly therefrom; whereby said fingers may 40 engage the rear ends of such cards or envelopes, after they have been pulled out of such magazine, and continue to exert a positive feeding action thereon after they are in such guides and are no longer in contact with the surface of such 45 drum.
- 45 12. A combination such as defined in claim 11 in which said fingers are pivoted on a member rigidly connected to said drum, and provided with spring means yieldingly holding them normally 50 in positions substantially radial of said drum.
- 50 13. A combination such as defined in claim 11 in which said fingers are adjustable circumferentially of said drum.
- 55 14. A combination such as defined in claim 1 in which said gate consists of a single solid plate.

HARMON P. ELLIOTT.
